CURRENT DIFFERENTIATED TIMING MECH-
ANISM FOR THE PURPOSE OF TRIPPING
CIRCUIT BREAKERS OR SWITCHES

Bruce O. Watkins, Tucson, Ariz.

Application August 29, 1941, Serial No. 408,731

4 Claims. (Cl. 200—97)

(Granted under the act of March 3, 1883, as
amended April 30, 1928; 370 G. G. 757)

The invention described herein may be manufactured and used by or for the Government of the United States for governmental purposes without the payment to me of any royalty thereon, in accordance with the provisions of the act of April 30, 1928 (ch. 460, 45 Stat. L. 467).

My invention relates to a current differentiated timing mechanism for the purpose of tripping a circuit breaker or switch and is applicable primarily to lines supplying power wherein it is desired to cut off the current within a definite period after the current exceeds a predetermined value.

In the drawing in which like reference characters designate like parts,

Fig. 1 is an elevational view partly in section of my timing mechanism,

Fig. 2 is an elevational view at right angles to that of Fig. 1,

Fig. 3 is a schematic view of a modification of 20 the structure illustrated in Figs. 1 and 2,

Fig. 4 diagrammatically illustrates a plurality of circuit breakers, or switches provided with my invention, connected in a series system, and

Fig. 5 diagrammatically illustrates my invention as applied to a single circuit breaker, or automatic switch.

In Figs. 1 and 2 I have illustrated a case 1 the back 2 of which supports a bracket 3, on the under side of which is mounted a solenoid winding 4, the form 5 of which supports a casing 6 which with the bracket 3 forms bearings for the solenoid core mechanism 7.

This mechanism includes a shaft 8, the reduced portion 9 of which carries a sliding armature 10 having one conical end 11 for purposes to be hereinafter described.

Around that portion of the shaft 8 which extends below the casing 6 I provide a compression spring 12 which, positioned between the casing 6 and the flanged end 13 of the shaft 8, moves the core mechanism 7 to the position illustrated when no current flows in the solenoid winding 4.

At the opposite end of the shaft 8 I provide a sliding joint in the nature of a dash-pot structure 45 14 carrying a rack 15 which engages the pinion 16 mounted on a shaft 17 mounted in bearings 18 in a support 19 mounted on the back 2 of the case 1. This nature of the joint 14 is such that it can transmit tension only.

The shaft 17 is driven by a spring 20, the speed of rotation of the shaft being controlled by a fly-wheel 21 or other suitable mechanism. In the several figures I have illustrated this fly-wheel as a cam for operating the pin coupling 22 55

for actuating the trip mechanism of a circuit breaker or automatic switch, when connected in the manner diagrammatically illustrated in Fig. 5.

The solenoid winding 4, the armature 10 and the spring 12 are designed in such a manner that when the winding 4 is connected in series in a line 23 containing a circuit breaker or automatic switch 24 a current of predetermined value will flow in the line without actuating the armature 10. When the current increases above this value the armature 10 drives the shaft 8 upward until the spring pressed latch 25 engages in the detent 26 in the shaft 8. The spring 20 then starts the fly-wheel 21 and depending upon the relative inertia of the fly-wheel and the spring, a predetermined interval of time elapses before the wheel 27 of the coupling 22 drops in the recess 28 of the fly-wheel, thus tripping the circuit breaker. When current flow through the solenoid coil stops, the armature 10 drops back on the shaft 8, the conical end forcing the latch 25 out of the detent 26 permitting the spring 12 to return the elements to the position illustrated.

In Fig. 3 I have shown the elements in horizontal position with the armature 10' fixed on the shaft 8 and a magnetic latch 25' in lieu of the spring pressed latch of Figs. 1 and 2.

In each of the structures, once a predetermined value of current is exceeded the time required to trip the circuit breaker or switch is independent of the current, and dependent only on the setting of the timing mechanism.

This principle makes it possible to use a large number of circuit breakers in series on a given system as illustrated in Fig. 4, wherein, for example, the timing mechanisms T₁, T₂, T₃ in block A, remote from the power source, are set to start operation at 20 amperes current, timing mechanisms T₄, T₅, T₆ in block B, less remote from the power source, at 35 amperes current, and timing mechanisms T₇, T₈, T₉ in block C, still less remote from the power source, at 50 amperes current, and the timing mechanism set so that the circuit breakers actuated by timing mechanisms T₁, T₄ and T₇ will trip out in 0.2 sec.; T₂, T₅ and T₈ in 0.4 sec.; and T₃, T₆ and T₉ in 0.6 sec. In this manner should the fault current occur at a point remote from the power source, the value of the fault current determines which circuit breakers of the several banks are tripped out. After the current ceases to flow the circuit breakers automatically reset out to the one nearest the source of trouble.

The circuit breakers T₁, T₂, etc., indicated in

groups A, B and C in Fig. 4, are tripped by controlling mechanism such as is shown in Fig. 1. The mechanisms controlling breakers T_1 , T_2 and T_3 (group A, Fig. 4) have a coil 4 of a certain rating, which, for example, may be X amperes, while the mechanisms controlling the circuit breakers T_4 , T_5 and T_6 (group B, Fig. 4) have a coil rating of Y amperes which is greater than X amperes, and the circuit breakers T_7 , T_8 and T_9 (group C, Fig. 4) have a coil rating of Z amperes which is greater than Y amperes. The coil 4 and its armature 10 are so proportioned that the coil raises the armature and starts the mechanism on any current greater than n times the rating, where n is any desired figure greater than the integer 1. Thus the mechanisms for the circuit breakers T_1 , T_2 and T_3 in group A will start operating on a current greater than nX amperes, while those for the circuit breakers T_4 , T_5 and T_6 in group B will start operating on a current greater than nY amperes and those for the circuit breakers T_7 , T_8 and T_9 in group C will start operating on a current greater than nZ amperes.

Since the amount of current in a short circuit on any radial electric system decreases as the distance from the power source increases, the coil ratings in each group A, B and C are stepped down from source to end.

Assuming that a short circuit occurs on a system on the load side of breaker T_1 , and that the short circuit current is greater than nX amperes, but less than nY amperes or nZ amperes, the three timing mechanisms controlled by circuit breakers T_1 , T_2 and T_3 will start simultaneously.

However, the setting of the spring 20 in the support 19 is set for a certain time, for instance 0.2 second on the mechanism for circuit breaker T_1 , while for the circuit breaker T_2 , the mechanism is set for a greater time for instance 0.3 second, and for the circuit breaker T_3 the mechanism is for a longer time for instance 0.4 second. Thus, rotation of the fly-wheel 21 brings its notch 28 under the roller 27, after 0.2 second for the mechanism for the circuit breaker T_1 . Since the mechanisms for the circuit breakers T_2 and T_3 are adjusted for a longer time they are recycled before tripping their respective circuit breakers by the spring 12 as soon as the short circuit is removed by the circuit breaker T_1 . This disconnects the line beyond circuit breaker T_1 , but all other lines remain energized, and since the short circuit current was less than nY or nZ amperes, the mechanisms for the circuit breakers T_4 to T_9 in groups B and C did not operate.

If there is a short circuit on the line between circuit breakers of group A and those of group B, the group B mechanism coils 4 would be adjusted so that the trip would occur on nY amperes, which would be short circuit current between circuit breakers T_3 and T_4 . The timing for the mechanism for T_4 circuit breaker would be set, for instance, for 0.2 second; that for T_5 circuit breaker for 0.3 second, and that for circuit breaker T_6 for 0.4 second, as for the circuit breakers in Group A. On a line fault between circuit breakers T_3 and T_7 operation similar to that just described above will occur.

Having thus described my invention, what I claim is:

1. In a delay mechanism for tripping-out circuit breakers and the like having a trip-out

mechanism, the combination of a rotatable cam adapted in one position to actuate said trip-out mechanism, a spring adapted to rotate said cam from a position remote from said actuating position to said actuating position at a predetermined rate of acceleration, a second spring more powerful than the first adapted to rotate said cam from said actuating position to said remote position and electro-mechanical means for overpowering said second spring and permitting said first named spring to rotate said cam at its predetermined rate of acceleration.

2. In a delay mechanism for tripping out-circuit breakers and the like having a trip-out mechanism, the combination of a rotatable cam adapted in one position to actuate said trip-out mechanism, a spring adapted to rotate said cam from a position remote from said actuating position to said actuating position at a predetermined rate of acceleration, means for rotating said cam from said actuating position to said remote position comprising a pinion attached to said cam, a rack in engagement with said pinion, a shaft arranged in the plane of said pinion, a spring for urging said shaft away from said pinion and a joint between said rack and said shaft transmitting tension only, and a solenoid, the armature of which is attached to said shaft and adapted to drive said shaft toward said pinion upon a predetermined current flow in the coil of said solenoid and permitting said first named spring to rotate said cam at its predetermined rate of acceleration.

3. In a delay mechanism for tripping-out circuit breakers and the like having a trip-out mechanism, the combination of a rotatable cam adapted in one position to actuate said trip-out mechanism, a coil spring adapted to rotate said cam from a position remote from said actuating position to said actuating position at a predetermined rate of acceleration, a pinion attached to said cam, a rack in engagement with said pinion, a shaft connected to said rack by means of a joint transmitting tension only, a compression spring more powerful than the coil spring engaging said shaft and adapted to rotate said cam from said actuating position to said remote position through said joint, rack and pinion, and a solenoid, the armature of which engages said shaft for compressing said compression spring and relieving said joint of any tension and means for locking said compression spring in its compressed position and permitting said coil spring to rotate said cam at its predetermined rate of acceleration.

4. In a delay mechanism for tripping-out circuit breakers and the like having a trip-out mechanism, the combination of a solenoid winding adapted to be connected in series with said circuit breaker, an armature within said solenoid adapted to be driven in one direction by current flow through said winding, a shaft connected to said armature, a spring at one end of said shaft for urging the shaft in a direction opposing movement by said armature, a timing mechanism, means at the other end of said shaft for starting said timing mechanism and means actuated by said timing mechanism after a predetermined lapse of time for actuating the trip-out of said circuit breaker.

BRUCE O. WATKINS.
